UNITED STATES PATENT OFFICE.

GEORGE HENRY DENISON, OF LEEDS, ENGLAND.

WEIGHING-MACHINE.

No. 802,271.

Specification of Letters Patent.

Patented Oct. 17, 1905.

Application filed March 23, 1905, Serial No. 251,674.

To all whom it may concern:

Be it known that I, GEORGE HENRY DENISON, engineer, a subject of the King of Great Britain and Ireland, residing at Hunslet Foundry, Leeds, in the county of York, England, have invented new and useful Improvements in Weighing-Machines, of which the following is a specification.

My invention relates to improvements in weighing-machines and their adjuncts, by which loads have their weights automatically recorded.

The object of my invention is to provide an automatically recording or registering weighing-machine and its adjuncts such that an unskilled attendant may be intrusted with its management without fear of incorrect results, his only duty being the turning of a handle or handles.

I will describe with reference to the accompanying three sheets of drawings first an arrangement according to my invention which dispenses with the necessity of an inclined rail or tram way.

Figure 1 is a general plan more or less diagrammatic of a weighing-machine constructed according to my invention, all the operating levers and handles being shown approximately in mid-position. Fig. 2 is a rear elevation showing a truck on the weighing-machine and retained in position by an arrangement of arms or levers and controlling-cam before the recording mechanism has been set in motion. Fig. 3 is a similar view showing the position into which the arms or levers have been moved by the rotation of the recording-shaft in order to allow the truck to move or to be moved off the weigh-table. Fig. 4 is a rear elevation showing the fulcrum end of the steelyard.

Fig. 5 is a longitudinal elevation showing the steelyard and other parts of the apparatus connected therewith. Fig. 6 is an elevation viewed from the line X Y in Fig. 1 of the cam and levers by which the steelyard is gripped.

Fig. 7 is a similar elevation showing the measuring-quadrant in action. Fig. 8 is a similar view showing the quadrant returned by the cam and the recording-wheel moved proportionately round. Fig. 9 is a view similar to

Fig. 6, showing the steelyard released. Fig. 10 is an elevation of the mercurial balance and dash-pot, and Fig. 11 is an enlarged section of the dash-pot and its plunger. Fig. 12 is an enlarged view of the cam shown in Figs.

2 and 3. Fig. 13 is a side view corresponding to Fig. 12, showing the spring-stud and

slot of the "reversing-gear." Figs. 14, 15, and 16 show an alternative arrangement of mechanism for retaining a truck on an inclined weigh-table until the weight has been recorded. Fig. 2^A shows in elevation how the mechanism shown in Figs. 2 and 3 may be operated by an eccentric, if desired.

The same references are used to indicate corresponding parts in all the figures, and the arrows show the direction of rotation. In order to secure clearness, all the figures are more or less diagrammatic, and in some figures--as, for instance, in Figs. 2 and 3--portions are cut away to save space.

A load to be weighed is brought along a tramway or other suitable course and pushed onto the weigh-table, which may be slightly inclined, the load being held stationary against a buffer or stop. When the weight of the load has been recorded, but not before, the said load is permitted to automatically pass off the weigh-table. When the load is resting in position against the buffer or stop on the weigh-table, the attendant proceeds to record the load by means of a handle pivoted on the frame of the machine. A predetermined number of turns of this handle puts the weighing mechanism through the several phases of its action as follows: First, the load raises or rather has raised the steelyard, the latter coming to a prompt stand by the action of (preferably) a mercurial balance or other similar dash-pot action, Figs. 5, 10, and 11; second, the arms of the mechanism for gripping the steelyard and holding it firmly in its raised position then come into action, Fig. 6; third, the measuring-gear, consisting of a pivoted quadrant device, falls over and measures the height of the now fixed steelyard, Fig. 7; fourth, the quadrant is returned and made to register the angle through which it had moved on a finely-divided ratchet-wheel, and so record the true weight of the load, Fig. 8; fifth, the steelyard-gripping gear is then released, Fig. 9, and, sixth, the whole mechanism is brought to its original position and the load released. At any time after the steelyard has been gripped the stop on the weigh-table can be arranged to be withdrawn by the mechanism and the load allowed to pass off from the weigh-table, after which the said stop may be replaced. When the use of an inclined plane or track is not suitable, an arm or other device may be so arranged as to allow the load to be moved off the weigh-table, (by hand,) the said arm be-

ing operated by the hand-wheel. The arrangement illustrated shows this particular one in which the inclined track is not relied on to cause the load to automatically pass from the weigh-table. The whole arrangement is such that the attendant cannot touch or get onto the load or in any way interfere with the correctness of the recorded weight, the turning of the handle or hand-wheel (clear of everything) being all he has to do when recording the weight.

Cams or their equivalents B, C, and D, mounted on the main shaft A of the apparatus, actuate the various pieces of mechanism, and these several portions are for the sake of distinction designated on the drawings by a number in connection with their cam-letter. Thus all parts B', B'', and so on, belong to the same gear worked by the cam B.

The attendant's handle E is carried on an arm or wheel E', mounted on a shaft E'', suitably supported on the standard or frame of the machine, and this shaft carries the pinion E', which is in gear with the spur-wheel E'' on the main shaft A. (See Figs. 12 and 13.)

The weigh-table F is arranged lengthwise longitudinally with the track F' and has the usual system of compound levers which terminates at the end F'' under the rear end of the steelyard G.

The steelyard has widely-spread fulcrum-points at G' and G'', so that its extreme end G'' will move steadily. At G' is arranged a mercurial balance (supported on the machine-frame) whose dash-pot action steadies the movement of the steelyard. The free end G'' of the steelyard lies close to the machine-frame near the gripping device. Fig. 10 shows the float or plunger G'' of the dash-pot standing in the mercury G''. The float or plunger G'' is hollow, and the head of the float has an air-hole G'', Fig. 11, and in the bottom thereof at G'' is a contracted orifice, these insuring a steady action of the steelyard. The length of the float or plunger is such as not to disturb the surface of the mercury in its movements. Suspended from the steelyard is a steadyng-ball G'', which is made hollow to receive adjusting-weights, and at the point of suspension (see Fig. 5) is a sliding piece G'' capable of being adjusted in position along the steelyard by the screw G'' and fixed in its adjusted position by fixing-screws.

The cam B governs the gripping-gear through the intervention of the heavily-weighted end B' of the bell-crank lever, (fulcrumed at B''), whose shorter arm B'' when released by the cam B securely grips, by means of the tie-rod B', the end G'' of the steelyard G. This tie-rod B' draws the lever B'' (fulcrumed at B'') tight, thus gripping the steelyard firmly against the fixed part of the apparatus. (See Fig. 6.) An adjusting or sleeve nut should be fixed on the rod B', as shown at B'', to adjust the length of the rod B'. The cam

is so arranged that the grip is not given before the steelyard has taken up the proper position due to the load. Directly the steelyard is gripped the measuring phase commences by the cam C retiring and allowing a bell-crank lever, fulcrumed at C'', with arms C' and C'', to come into play. This bell-crank draws over the quadrant C'', (connected to C' by the tie-rod C', fitted with an adjustable sleeve-nut C'' for adjusting its length,) which quadrant falls against the steelyard. The shape of this quadrant and the position of its axis C'' (see Fig. 7) are such as allows it to fall through equal angular distances for equal movements of the steelyard, which steelyard is also arranged to lift through equal angular distances for equal increments of load, due to equal displacements of mercury by the plunger G''. (See Fig. 7.) It is important that the quadrant shall fall with promptitude, but with as light a blow as possible on the steelyard, lest it should move it and measure erroneously. To this end I mount a short-weighted lever C'', whose fulcrum is at C'' and whose downward fall is limited by the stud C''. This lever is lifted, as in Fig. 8, on the return stroke of the cam and is ready to give a prompt start to the quadrant; but it leaves it to fall alone with a minimum of momentum. The quadrant having fallen forward as far as the then position of the steelyard has allowed, the cam C continues to revolve and forces back the quadrant to its normal position or zero point of measurement, as shown in Fig. 8, where the steelyard zero position is pointed out by the dotted lines. In traveling back it carries with it proportionately a wheel C'', mounted on the same axis C'', and thus records on the periphery of this wheel the amount last measured by the fall of the quadrant. This is accomplished by having finely-divided teeth on the wheel C'', supplemented with a set of ratchets, (shown at C''), which greatly increase the effective subdivisions. For security similar non-return ratchets are provided at C'' and to prevent overrunning a brake C'', with a spring-washer or like adjustment at C'', is provided. The brake which nips the sides of the wheel C'' in its forked end is constantly in action, being lightly secured by a bolt C''. The adjusting or sleeve nut C'' renders it possible to throw the quadrant back exactly to its zero point and no farther. From the axis of the wheel C'' suitable gear is connected up to any desired counter. This is not shown, as its action will be understood without complicating the drawings. The next phase is the release of the gripping-gear, which will be easily followed from an inspection of Fig. 9, where the cam has so far continued its revolution as to have lifted the gripping-lever B'' away from steelyard G.

It now remains to describe a leading and important feature of the whole arrangement—viz., the mode of making sure of the record-

ing of the weight of every single load before it passes from the weigh-table. This is forced on the attendant while he works the handle of the recording mechanism. On Fig. 1 it will be seen that there is a rock-shaft D' extending along the center of the track and provided with arms or stops D² and D³ at each end. This shaft D' is fitted so near the ground that trucks can run on the track clear of the shaft, but not so with regard to the clearance of these stops D² and D³, which, if not moved, one or the other will engage with the axles of the trucks. In order to pass a truck onto and off the weigh-table, the shaft must be rocked or partially rotated so as to move the arm D³ at the entrance end of the table downward out of range of the axle of the truck. As the truck gains access to the table the arm D² at the other end of the rock-shaft is at the same time brought up into position in the path of the forward axle of the truck to prevent the truck from running off the weigh-table while the weight thereof is being registered. That having been accomplished, the shaft D' must be rotated in the other direction, whereupon the stop-arm D² is depressed to below the shaft-level, the truck being then free to pass off the weigh-table. As one of these movements of the shaft D' can be worked only by the recording apparatus, it follows that every truck must be dealt with by that mechanism. This is effected as follows: On the rocking shaft D' is an arm D⁴, which is connected by a rod D⁵ to an arm D⁶ on a rock-shaft D^X, carrying another arm D^{XX}, which is connected by a rod D⁷ to a lever fulcrumed at D⁸. The rod D⁷ imparts, through the movement of the arm D⁶, rocking motion to the lever, fulcrumed at D⁸, whose outer end carries the roller D⁹, which is acted on by the cam D. The cam D is integral with or fixed to a plate D¹⁰, fast on the main shaft A. (See Figs. 1, 12, and 13.) A complete rotation of this cam and plate from the position shown in Fig. 2 throws the truck-releasing mechanism (the D series) into the position shown in Fig. 3, in which position the truck whose weight has been recorded can be rolled off the weigh-table. A spring-catch D¹¹ in the pin of the roller D⁹ has now fallen to the bottom of a slot or pathway D¹² in the cam-plate D¹⁰, and all further movement of the hand-wheel E' is stopped for the time being. The truck having left the weigh-table, the attendant allows the next truck of the series to pass onto the weigh-table; but this he can only do by returning the rocking shaft D' to its first position, Fig. 2, as the stop D³ prevents the truck obtaining access to the table. To accomplish this, he moves the reversing-lever D¹³ (suitably connected with a rocking shaft D¹⁶, connected to the rod D⁵) over to the opposite side, (shown in Fig. 2,) and this he is able to do at this particular position of the cam-plate D¹⁰. This action while admitting the truck onto the table also

brings the arm D² into position to prevent the truck from running off it without being weighed. When roller D⁹ on the lever fulcrumed at D⁸ is raised, (by the reversing action,) a central pin or stud of the spring-catch D¹¹ is pushed back against its spring and is also pushed up the inclined path D¹² in the cam-plate D¹⁰ until it enters the deep recess D¹⁴ at the top of the pathway D¹². The shaft A can now be rotated by means of the handle E, another inclined pathway D¹⁵ allowing the spring-catch D¹¹ to gradually mount once more to the face of the cam-plate D¹⁰, ready to again enter into the slot D¹² when the next cycle of the operation is completed. The extent of movement of the actuating-handle is such that ample time is given for each successive cycle of operations. As before explained, a spring-catch D¹¹ is arranged to stop the hand-wheel at the right place, (this is where I reverse,) and shortly before this a suitable signal may be arranged to give warning. The said spring-catch would of course require to be raised at the next start, and this is done automatically when the attendant pulls up the handle D¹³, as already described. The whole of the automatic mechanism is arranged in a lock-up hub. This is not shown but will be understood as to its position by examining the bed-plate on the right of Fig. 1. A covered way (see dotted lines in Fig. 3) protects the truck when on the weigh-table. The handles E and D¹³ need be the only items left exposed, all others being under cover excepting the rocking shaft D' and its stops, which are made strong enough to resist rough usage.

When it is desired that the truck may be allowed to roll away as soon as the weight is recorded, an inclined track and weigh-table is provided. Such an arrangement is shown by Figs. 14, 15, and 16, in which D² and D³ are, as before, stops; but instead of rocking they slide off and on their respective positions on the rail. D' is a double-ended lever corresponding to the rocking shaft D' in Fig. 1 for working the sliding stops last mentioned. The horizontal rod at D⁵ couples D' to D⁶ (as in Fig. 1) and so connects all with the recording apparatus. The ends of the lever D' enter (loosely) slots in the stops D² and D³, (see Fig. 16,) so as to allow the weigh-table to take up its proper position due to the load thereon. The *modus operandi* is practically the same as before—viz., when a load has been weighed and has left the weigh-table the action of the rod D⁵ has pushed the stop D³ (in the rear) across the rear stopping position and all is blocked there. To again gain access to the table, the attendant pushes over the handle D¹³, Figs. 1, 2, and 3, and in so doing clears the line at D³, but blocks it in front. The weighing and recording of the new load clears the line at D² and blocks it at D³, and so on. As there would be considerable

friction in moving the sliding stops D^2 and D^3 , friction-rollers D^{16} and D^{17} may be resorted to, for example, as shown in plan view near the stops D^2 and D^3 .

5 By the following arrangement the reversing-lever D^{13} may be dispensed with. As soon as the steelyard has been firmly gripped the stop-arm D^2 may be arranged to automatically withdraw, followed in due course by the 10 automatic withdrawal of the arm D^3 , which restores the parts to the first position, and so on. This arrangement, which is designed for an inclined track (on which the trucks are able to restart themselves) dispenses with an attendant, the recording mechanism being driven by any convenient belt or by a convenient motor, electrical or otherwise. In this arrangement an eccentric D or its equivalent (see Fig. 2^A) is made to take the place of the 15 cam D to rock the lever D^6 direct, as shown. The angular advance of the eccentric must be such as to release the weighed truck directly the steelyard is properly gripped in order to allow time for the return stroke to accomplish the next admission to the weigh-table 20 from the rear.

The line right across the weigh-table is never clear, for when there is a clear approach to this table there is a "block" in front, and 30 when the line is "clear" in front there is a block behind—and this must be understood throughout.

Referring to the steelyard G , the weight G^{12} may be suitably placed to represent the tare 35 weight of the truck, so that the net weight may be correctly recorded.

I claim as my invention—

1. An automatic weighing and registering machine, comprising a weighing-table and 40 means for blocking and clearing the way across said table, in combination with a steelyard, a dash-pot for steadyng the same, means for gripping and releasing the steelyard, and means for recording the weight indicated 45 thereby, all of said means connected to and worked from one shaft.

2. An automatic weighing and registering machine, comprising a weighing-table and means for blocking and clearing the way across 50 said table, consisting of a shaft, means on said shaft for engaging the body to be weighed while on said table, and means to prevent another body from passing onto said table at the same time, in combination with a main operating-shaft, a cam thereon, and means connected therewith and with said blocking and clearing means for operating the latter.

3. An automatic weighing and registering machine, comprising a weighing-table, and 60 means for blocking and clearing the way across said table, consisting of a shaft, a projection thereon adapted to stop the body after it passes onto the weighing-table and a projection at an angle thereto adapted to prevent a 65 second body from passing onto said table, and

means for rocking said projections on said shaft to permit the first body to pass off and the second body to pass onto said table.

4. In an automatic weighing and registering machine, a weighing-table, means for blocking and clearing the way across said table, a steelyard, two spread fulcrum-points therefore, means for steadyng the movement of said steelyard and means comprising a hollow body for adjusting purposes, secured to said 75 steelyard by means passing through said steadyng means.

5. An automatic weighing and registering machine, comprising a weighing-table, a main operating-shaft and means connected with said 80 shaft for blocking and clearing the way across said table, in combination with a steelyard, a dash-pot for steadyng the same, means for gripping and releasing said steelyard and a cam on said main operating-shaft for operating 85 all of said means.

6. An automatic weighing and registering machine, comprising a weighing-table, a main operating-shaft, a cam thereon and means connected with said cam for blocking and clearing 90 the way across said table, in combination with a steelyard, a dash-pot for steadyng the same, means for gripping and releasing said steelyard and means for measuring and recording the movement of said steelyard, all 95 of said means operated from said main operating-shaft.

7. An automatic weighing and registering machine, comprising a main operating-shaft, a weighing-table, and a steelyard, means on 100 said table for blocking the way across said table, and means for operating the same, means for gripping said steelyard, means for measuring the movement thereof, means for releasing said steelyard, and means for clearing 105 the way across said table, all of said means being operated by said main operating-shaft.

8. An automatic weighing and registering machine, including a main operating-shaft, means for rotating said shaft, a grooved plate 110 on said shaft and means connected therewith to prevent reversal of the rotation of said shaft until the cycle of operations is complete.

9. In an automatic weighing and registering machine, a main operating-shaft, a steelyard, and a weighing-table, an inclined tramway running across said table, and means connected with and operated by said main shaft to bring about a continuous cycle of 115 operations without allowing an unweighed truck to pass forward.

In testimony whereof I have signed this specification in the presence of two subscribing witnesses.

GEORGE HENRY DENISON.
